LOOSE LEAF BINDER

Nelson S. Welk, Athens, Ohio, assignor to The
McBee Company, Athens, Ohio, a corporation
of Ohio

Application June 16, 1933, Serial No. 676,052

6 Claims. (Cl. 129—8)

My invention relates to that class of devices which are designed to hold a plurality of loose leaves and which may, if desired, be filled up from time to time. It is well known that ring books of this type even if equipped with a one-inch diameter ring will hold only approximately one-half inch of sheets. Moreover, if you desire to insert or remove a sheet from the center portion of the bound sheets, it is an extremely difficult job because of the fact that you have to swing part of the sheets over on one half of the rings and the other portion remains on the remaining half and if you do not wish to divide or make your insert exactly in the center it is necessary to remove a number of sheets and replace them all of which is time wasting and uneconomical.

My invention has for its object to provide means for binding a number of loose leaves in a book in which the binder will hold its full capacity and in which it is possible to gain access to a leaf or to insert a leaf at any part of the volume without the slightest difficulty.

My means of accomplishing the foregoing objects may be more readily understood by having reference to the accompanying drawings which are hereunto annexed and form a part hereof, in which

Fig. 1 is an isometric perspective view of a fragmentary portion of a binder with my attachment, the parts being shown in separate position for the sake of clearness;

Fig. 2 is a top or plan view of the binder with the parts in assembled position;

Fig. 3 is an end view of the same;

Fig. 4 is a plan view of the device with the impaling pins separated from the metal back;

Fig. 5 is an end view of the same; and

Fig. 6 is a section taken on the line 6—6 in Fig. 4.

Similar reference numerals refer to similar parts throughout the entire description.

As shown in the drawings, the binder is attached to a pair of covers 1 and 2. It comprises a metal back 3, one edge 4 of which is bent at right angles thereto so that the metal back in cross section presents the appearance of an L.

A hinge 5 is provided on the other edge of the metal back and a hinged bar 6 is secured thereto by means of a hinge pin 7 in the usual manner. This hinged bar 6 is provided with a plurality of impaling pins 8 and has a number of perforations 9 formed intermediate the impaling pins. As shown the pins are three in number though it will be obvious they can be any number desired. The ends 10 of the hinged bar

are bent upwardly for the purpose of forming a spring lock which will be hereinafter explained. The pins 8 are arcuate but on a very large radius so as to be almost straight and terminate in points which are adapted to enter but not pass through apertures 11 formed in a detachable bar 12 which also carries impaling pins 13 which are adapted to enter the apertures 9 formed in the hinged bar 6.

The detachable bar 12 is preferably formed of 10 spring steel and has mounted adjacent its ends two locking pins 14 and 15. These pins are adapted to register with apertures 16 and 17 formed in the narrower portion 4 of the L shaped metal back 3. Notches 18 are cut in the 15 ends of the detachable bar 12 and these notches are engaged by the upper ends 19 as clearly seen in Figs. 3 and 5. The operation of the device is as follows:

The loose leaves (not shown) are provided with 20 perforations adapted to register with the impaling pins and are placed upon the pins 8. The pins 13 are then inserted in the intermediate perforations and as the points on these pins are smaller than the apertures 9 so that 25 only the points of the pins can enter the apertures the pins cannot pass through them. The hinged bar 6 is then swung over until it reaches the position shown in Fig. 3 when the detachable bar will pass beneath the portion 4 of the L 30 shaped metal back 3 and the pins 14 and 15 will be brought into register with apertures 16 and 17. Due to the resiliency of the metal, out of which the detachable bar 12 is formed, pins 14 and 15 will at once enter the holes and the 35 ends 18 of the upwardly bent portions 10 of the hinged bar will engage the notches 19 in the detachable bar 12 and serve as a spring lock for holding the bar 12 firmly in place and will also prevent the bar 12 from sliding forward. It 40 will be obvious from the foregoing description of the pins 8, since they extend the entire width of the volume, that any desired number of leaves can be left impaled upon them when the detachable bar is removed for the purpose of gaining 45 access to any leaf without the slightest difficulty regardless of its location.

It will also be clearly apparent that the space between the hinged bar and the detachable bar can be completely filled with loose leaves.

To remove the leaves the ends of the detachable bar are pressed downwardly until the pins 14 and 15 are disengaged from the apertures 16 and 17 when the volume can be swung upon the hinge 5 and as soon as the detachable bar 55

is in the position shown in Fig. 5 it can be lifted up with as many leaves as desired leaving the remainder on the pins 8 or it can be lifted entirely off of the leaves and all the leaves in the volume will be left on the pins 8.

By making the impaling pins slightly arcuate in form I facilitate the flat opening of the book.

It will be apparent from the foregoing that I have provided a structure which entirely overcomes the objectionable features pointed out in the ring binders used in this class of work and have attained the result by means of a very simple and economical form of structure.

It may well be in practice that some other form of locking the detachable bar to the metal back will be found and although I have shown and described the specific type of structure for this purpose, I wish to be understood that these illustrations are solely for the purpose of showing a preferred embodiment of the invention and not with any intention of being limited to the specific structure shown and described except as such limitations may appear in the hereinafter appended claims.

Having described my invention what I regard as new and desire to secure by Letters Patent is:

1. In a binder for loose leaves, a cover, a metal back L shaped in cross section secured to said cover, there being an aperture adjacent each end of the shorter portion of said L, a hinge on one edge of said back, a bar hinged thereto, a plurality of impaling pins fixedly secured to said bar, there being perforations in said bar intermediate said pins, a detachable bar having perforations therein which register with said pins, pins on said detachable bar which register with the perforations in the hinged bar, a locking pin on each end of said detachable bar adapted to enter the respective apertures in the shorter portion of said L and means on said hinged bar to hold said detachable bar in place when the locking pins are engaged with said apertures.

2. In a binder for loose leaves, a cover, a metal back L shaped in cross section secured to said cover, there being an aperture adjacent each end of the shorter portion of said L, a hinge on one edge of said back, a bar hinged thereto, a plurality of impaling pins fixedly secured to said bar, there being perforations in said bar intermediate said pins, a detachable bar having perforations therein which register with said pins, pins on said detachable bar which register with the perforations in the hinged bar, a lock on each end of said detachable bar adapted to enter the respective apertures in said L, the ends of said hinged bar being bent upwardly to form a spring lock to hold said bar in place, to constitute means to hold the detachable bar in place when the locks are engaged with said apertures.

3. In a binder for loose leaves, a cover, a metal back L shaped in cross section secured to said cover, there being an aperture adjacent each end

of the shorter portion of said L, a hinge on one edge of said back, a bar hinged thereto, a plurality of impaling pins fixedly secured to said bar, there being perforations in said bar intermediate said pins, a detachable bar having perforations therein which register with said pins, pins on said detachable bar which register with the perforations in the hinged bar, a lock on each end of said detachable bar adapted to enter the respective apertures in the shorter portion of 10 said L.

4. In a binder for loose leaves, a cover, a metal back L shaped in cross section secured to said cover, there being an aperture adjacent each end of the shorter portion of said L, a hinge on one edge of said back, a bar hinged thereto, a plurality of impaling pins fixedly secured to said bar, there being perforations in said bar intermediate said pins, a detachable bar having perforations therein which register with said pins, pins on said detachable bar which register with the perforations in the hinged bar, said perforations being shaped to permit the points of the pins to enter but not to pass through said bars, a locking pin on each end of said detachable 25 bar adapted to enter the respective apertures in said L and means on said hinged bar to hold said detachable bar in place when the locking pins are engaged with said apertures.

5. In a binder for loose leaves, a cover, a metal back L shaped in cross section secured to said cover, there being an aperture adjacent each end of the shorter portion of said L, a hinge on one edge of said back, a bar hinged thereto, a plurality of impaling pins fixedly secured to said bar, 30 there being perforations in said bar intermediate said pins, a detachable bar formed of spring metal having perforations therein which register with said pins, pins on said detachable bar which register with the perforations in the hinged bar, 35 a lock on each end of said detachable bar adapted to enter the respective apertures in the shorter portion of said L and means on said hinged bar to hold said detachable bar in place when the locking pins are engaged with said apertures.

6. In a binder for loose leaves, a cover, a metal back L shaped in cross section secured to said cover, there being an aperture adjacent each end of the shorter portion of said L, a hinge on one edge of said back, a bar hinged thereto, a plurality of impaling pins fixedly secured to said bar, there being perforations in said bar intermediate said pins, a detachable bar having perforations therein which register with said pins, pins on said detachable bar which register with the perforations in the hinged bar, means adjacent the ends of said detachable bar to detachably engage the apertures in the back to lock said bar to said back and means to hold said bar in place when said detachable means are engaging said apertures.

NELSON S. WELK.
